POWER TRANSMITTING IDLER WHEEL

John H. Rentschler, Edina, Minn., assignor to Minnesota Rubber Company, Minneapolis, Minn., a corporation of Minnesota

Filed May 8, 1968, Ser. No. 11,839

Term of patent 14 years

Int. Cl. D15—99

U.S. Cl. D55—1

FIG 1

FIG 2

FIG 3

FIG 4

FIGURE 1 is a perspective view of a power transmitting idler wheel embodying my design;

FIGURE 2 is a side elevational view of the same;

FIGURE 3 is a top plan view of the same; and

FIGURE 4 is a bottom plan view of the same.

All other side elevational views are identical to that shown in FIGURE 2.

I claim:

The ornamental design for a power transmitting idler wheel, as shown and described.
